UNITED STATES PATENT OFFICE.

THOMAS I. RANKIN, OF PHILADELPHIA, PENNSYLVANIA, ASSIGNOR TO
ABRAM COX STOVE COMPANY, OF SAME PLACE.

DESIGN FOR A HEATING-STOVE.

SPECIFICATION forming part of Design No. 35,114, dated September 17, 1901.

Application filed August 27, 1901. Serial No. 73,502. Term of patent 7 years.

To all whom it may concern:

Be it known that I, THOMAS I. RANKIN, a citizen of the United States, residing in Philadelphia, Pennsylvania, have invented and produced a certain new and original Design for a Heating-Stove, of which the following is a specification.

My design for a heating-stove is clearly illustrated in the accompanying drawing, which represents the stove in perspective.

The essential feature of the design is the ornamentation of the base, the body portion, and the rails at each side of the stove.

F is the base, containing the ash-pit and having an ash-pit door f. Depending from the base is a skirt or apron f'. The base is supported on suitable legs f². The apron f' is ornamented with flat foliated scrollwork, and the upper portion of each leg f² is ornamented by a double scroll in keeping with the scroll-work on the apron. The ash-pit door has a central medallion with a projecting rosette, and extending from each hinge is a foliated scroll, and on the opposite side of the door are scrolls in keeping therewith. The base of the stove is ornamented in keeping with the ornamentation on the door. The fire-chamber portion F' is ribbed, as shown, and above the fire-chamber is a flange f³, ornamented with a series of scrolls.

The body F² of the stove is ornamented in keeping with the ornamentation of the base. The fire-door F³, hung to the body F², is rounded at the top and has two medallions, the lower medallion being oval in form. Surrounding the medallions are foliated scrolls.

At each side of the stove are foot-rests f⁴, having arms extending to the base F and to the flange f³, and the rails of each foot-rest, as well as the arms, have scroll ornamentation thereon.

The dome-section F⁴ has a plain band or skirt, and above the skirt is a band ornamented by said foliated scrolls. The body portion of the dome is ornamented by flat scrollwork in keeping with that on the apron at f'. Mounted on the dome-section is a vase.

I claim—

The design for a heating-stove as herein described and as illustrated in the accompanying drawing.

In testimony whereof I have signed my name to this specification in the presence of two subscribing witnesses.

THOMAS I. RANKIN.
